UNITED STATES PATENT OFFICE.

EDWARD S. ADAMS AND WALTER H. ADAMS, OF COLUMBUS, OHIO.

STORAGE BATTERY.

1,391,089

Specification of Letters Patent. Patented Sept. 20, 1921.

Application filed July 12, 1920. Serial No. 395,555.

To all whom it may concern:

Be it known that we, EDWARD S. ADAMS and WALTER H. ADAMS, citizens of the United States, residing at Columbus, in the 5 county of Franklin and State of Ohio, have invented a certain new and useful Improvement in Storage Batteries, of which the following is a specification:

Storage batteries and particularly such as 10 are used in automobiles have caused a great deal of annoyance, trouble and expense owing to the instability of the connection of the pillar post with the jar cover. Such instability of connection frequently results in 15 fracture of the cover, leakage of the liquid contents of the battery and short circuiting and wastage of current.

The object of the present invention is, 20 principally, to provide an improved connection whereby the troubles recited are overcome or greatly mitigated.

The invention is embodied in the example 25 herein set forth, the features of novelty being finally claimed.

25 In the accompanying drawing forming part hereof—

Figure 1 is principally a longitudinal sectional view through the cover with attached plates in side view.

30 Fig. 2 is an end view broken off at the bottom.

Fig. 3 is a top plan view.

In the views 5 designates the cover of the socketed or "well" variety, the character 6 35 designating the socket thereof. Said socket 6 is of downwardly tapering form. 7 designates the plates or "grids" which are welded to the pillar post 8, as usual. The pillar post 8 has a threaded member or stem 9. Upon said stem we turn a thick solid nut 10 40 tapered to fit the socket 6. Recesses 10^a are formed in the upper end of the nut to receive a suitable wrench. The nut is preferably made of a thickness to lie flush with the top of the socket when turned home.

On the pillar post below the socket portion 6 is a ring washer 12 and in the bottom of the socket portion 6 is a ring washer 13. When the nut is properly turned down a

close, tight fit is secured. In practice we 50 turn in the nut while the cover is in a softened condition so that upon hardening the tightness of fit is accentuated.

With this construction it will be observed 55 that the connection is given extensive contacts in an axial direction of the stem generally speaking, hence great resistance to strains cross wise of that direction such as occur when the car is traversing rough roads. It will be further observed 60 that this extensive connection is secured without increasing the ordinary thickness of the cover. The cover is provided with the usual vent 14 for supplying water or other liquids to the jar.

65 In constructing the battery we propose to add to the pillar post a strip 15 of hard rubber or other non-conducting material to hold down the usual wooden separators 16. This strip is pinched between pliable lugs 70 17 formed on the lower side of the pillar post so as thereby to be kept in proper position.

The character 18 designates the cell connector, the open end of which is fitted down 75 over the top of the threaded stem of the pillar post, said stem being spread out and welded over the upper side of the connector to secure it in place.

What we claim is:

80 1. In a storage battery, the combination with a jar cover having a screw tapered socket open at its bottom, of a pillar post including a threaded stem to extend upward through the open bottom of said socket, and a tapered nut of lead threaded onto said stem and fitting in said socket.

85 2. In a storage battery having a jar and cover, the combination with battery plates secured on a pillar post and separators between the plates, of a hold-down for said separators consisting of a strip extending transversely over the upper edges of the separators, and means on the pillar post to engage and hold said strip, whereby the cover 90 can be removed without removing said strip.

EDWARD S. ADAMS.
